UNITED STATES PATENT OFFICE.

FRANK A. HOLLENBECK, OF SYRACUSE, NEW YORK.

DESIGN FOR A BICYCLE-SADDLE.

SPECIFICATION forming part of Design No. 28,434, dated March 29, 1898.

Application filed January 24, 1898. Serial No. 667,834. Term of patent 7 years.

To all whom it may concern:

Be it known that I, FRANK A. HOLLENBECK, a citizen of the United States, residing at Syracuse, in the county of Onondaga and State of New York, have invented and produced a new and original Design for Bicycle-Saddles; and I do hereby declare the following to be a full, clear, and exact description of the same, reference being had to the accompanying drawings, forming a part thereof.

My invention is a new and original design for bicycle-saddles; and it consists in the form and contour illustrated in the accompanying drawings and fully disclosed in the following description and claim.

Referring to the said drawings, Figure 1 is a perspective view of a bicycle-saddle embodying my design. Fig. 2 is a transverse sectional view of the same on line 2 2 of Fig. 1. Fig. 3 is a longitudinal sectional view on line 3 3 of Fig. 1.

The back edge *a* of the saddle is curved outwardly in the arc of a circle, the ends of the arc being curved sharply inwardly, as at *b*, to a point near the longitudinal center of the saddle and then converging to the point *c* of the pommel. The saddle has downwardly inclined or sloping edges *d* all the way around it and a deep longitudinally-disposed groove *e* running through the center. The outer edges *ff* of the saddle are higher than the central portions adjacent to the groove, and

the top portions of the saddle in rear of the narrowed pommel slope from said outer edges *ff* downwardly toward the center, as shown 35 at *g g* in Fig. 2, and also forwardly, as shown in Fig. 3. The portions *h h* of the top of the saddle at each side of the groove *e* extend in a substantially straight line from the back to the end of point of the pommel, as shown 40 in Figs. 1 and 3.

The foregoing constitute the leading features of my design.

Another feature of the design is the ornamental plates *k*, which are placed on the sloping edges of the saddle at two opposite points 45 at the outer sides of the saddle, as shown in Figs. 1 and 2.

Another feature of the design is an ornamental plate *l*, curved in cross-section, lying 50 in said groove, as shown, and having at its rear end a broadened portion, which extends down over the rear inclined face.

What I claim, and desire to secure by Letters Patent, is—

The design for a saddle for bicycles, substantially as herein shown and described.

In testimony whereof I affix my signature in presence of two witnesses.

FRANK A. HOLLENBECK.
